TO AMERICAN CAST IRON PIPE COMPANY, OF BIRMINGHAM, ALABAMA, A COR-
PORATION OF GEORGIA.

CUPOLA CHARGER.

Application filed May 18, 1926. Serial No. 109,826.

This invention is an improvement in cupola charger, and relates more particularly to a charger designed to distribute the charge in the cupola in even layers of uniform thickness.

In usual methods of charging cupolas, the charge is delivered either by dumping the charge into the cupola from the side, or by carrying the charge into the cupola and dropping it onto the preceding charge. In either case a relatively high stack is required, in order that the charge may fall a considerable distance, since in this way only can the charge be scattered or spread.

The long drop of the charge is objectionable for many reasons, among which may be mentioned the increased cost of installation, the arrangement requiring as it does a high stack cupola, and the breaking of the coke from the fall. A further objection is that the high drop of the charge injures the refractory lining of the cupola, and furthermore the arrangement is limited to small charges and hence to cupolas of relatively small capacity.

One of the primary objects of the present invention is the provision of a charger operated from the side, and near the level of the material in the cupola, requiring thus a minimum of drop for the charge.

A further object is the provision of mechanism in connection with the charger and operated by the movement thereof into and out of the cupola for distributing the charge over the entire area of the material already deposited in a layer of uniform thickness.

A further object is the provision of a charger utilizing a support for a charging box movable laterally into and out of the cupola, thereby to dump and remove the box with a minimum of exposure of the parts to the heat of the cupola.

With these and other objects in view the invention consists in the construction and novel combination of parts fully described hereinafter, illustrated in the accompanying drawings, and pointed out in the claims appended hereto, it being understood that various changes in the form, proportion, size and minor details of construction within the scope of the claims, may be resorted to without departing from the spirit of the invention.

In the drawings forming a part hereof:

Fig. 1 is a side view of the charger box, 55 with the cupola and associated parts in vertical section.

Fig. 2 is a section on the line 2--2 of Fig. 1.

Fig. 3 is a detail side view showing the box 60 in another position.

Fig. 4 is a top plan view of the switch or shifting pawl.

The present embodiment of the invention is shown in connection with the stack 1 of a cupola of usual construction, having the lateral charging opening 2, which is at about the highest level of the material in the cupola. A frame work 3 is arranged at the charging opening 2, and just below the same, and this frame work supports a pair of rails 4 which incline toward the charging opening from their outer ends, the frame work being constructed to support the rails in this position.

A carriage 5 of suitable construction is mounted to move upon the rails, the carriage having flanged wheels 6 which run upon the rails, and it will be evident that due to the inclination of the rails, the carriage is 80 biased by gravity to move toward the cupola.

A tilting frame or tipple 7 is pivoted to the front end of the carriage, the pivotal connection indicated at 8 being at a point remote from the front end of the frame. 85 The arrangement is such that above one-third of the length of the frame projects beyond the front end of the carriage as clearly shown. Any suitable pivotal connection may be provided, and the frame normally 90 seats upon the carriage as shown in Fig. 1.

A plurality of rails 9 is arranged in spaced relation transversely of the frame, at the ends and intermediate the ends thereof, and these rails serve as seats for receiving a 95 charger box 10. Guide plates 11 are secured to the frame at each side thereof, the plates being arranged in pairs, and so spaced laterally of the frame, that the charger box will fit between them. These plates prevent 100 lateral movement of the charger box when seated on the frame.

One end of the charger box is open, and the box is seated on the frame with the open end toward the cupola. The box has a depending flange or stop 11^a at the closed end,

which is the rear end when the box is seated on the frame, and this stop by its engagement with the rearmost rail 9 prevents the box from sliding off the frame when manipulated in a manner to be presently described.

The movement of the carriage and box toward the cupola under the influence of gravity is restrained and controlled by fluid under pressure apparatus. Said apparatus 10 in the present instance is constituted by a cylinder 12, in which is movable a piston 13. A flexible member 14 is connected at one end with the piston, and at the other with the carriage 5, the connection indicated at 15. 15 A pulley 16 is journaled in the frame work 3 over which the flexible member passes, and it will be evident that when the piston is moved outwardly, the carriage with its load will move toward the cupola. The fluid 20 under pressure which may be water, is derived from any suitable source, and controlled in any suitable manner.

Stops 17 are arranged at the lower end of the rails 4, for engagement by the wheels 6 25 to check the movement of the carriage and its load toward the cupola, and the stops are just within the charging opening 2. It will be noticed referring to Fig. 1, that one pair of wheels 6 is arranged at one end of the 30 carriage 5, while the other pair is arranged at about the center. Thus the front end of the carriage extends well beyond the front pair of wheels, and the forward end of the tilting frame extends well beyond the forward end of the carriage. The arrangement 35 is such that when the wheels 6 engage the stops 17, the forward end of the charger box will be near the rear wall of the cupola, as shown in Fig. 1, so that a part of the 40 charge will be dumped at the rear wall.

The carriage 5 is restrained from tilting movement under the weight of the load, by means of rails 18 which are secured to the frame work above and parallel with the rails 4. These rails 18 are in position to be 45 engaged by the rear wheel 6 of the carriage, thus to prevent tilting movement of the carriage under the weight of the load.

The position occupied by the charging box 50 on the tilting frame is determined by the stop 11^a, and the arrangement is such that there is no tendency of the frame to tilt with its load. Mechanism is provided for gradually tilting the frame and the box as it 55 moves toward the cupola, and to sharply increase the angle of tilt of the frame at the beginning of its return movement away from the cupola thereby to completely empty the box.

60 The said mechanism includes rollers 19 journaled at opposite sides of the tilting frame at the rear end thereof. These rollers run upon angle rails 20 secured to side plates 21 supported by the frame work 3. The 65 rails 20 diverge from the rails 4 toward the

cupola, that is the rails 20 incline away from the rails 4 toward the cupola, so that as the carriage and its load moves toward the cupola under the influence of gravity, the frame is tilted. The angle of tilt approaches that at which the material in the charging box would normally begin to discharge, but does not quite reach this angular inclination. As the box commences its return movement, the frame is further and sharply tilted sufficiently to overcome the static friction between the box and the material. As the material slides forwardly in the box, the box is withdrawn in the return movement, thus laying a uniform even layer from rear to front of the cupola, on the material indicated at 22 already in the cupola. The motion required to obtain this discharge is accomplished by a uniform pull of cylinder 12, and by means of pawls 23, and the path that rollers 19 follow between guide rails 24 and 26 to be described.

The mechanism for imparting the sharp tilt to the tipple and box includes switches or deflecting pawls 23 pivoted to the side plates 21, near the ends of the rails 20. The free ends of the pawls rest upon the rails 20, and as the carriage moves toward the cupola the rollers 19 will engage and lift the pawls and pass beyond them. The pawls are pivoted above the rails 20, and as the carriage starts its return movement, the rollers will move up the pawls thus imparting a sharp tilt to the charger box.

The pawls 23 are pivoted at the front ends of angle rails 24 secured to the plates 21, upon which the rollers 19 run as the carriage moves outward. The rails 24 incline upwardly slightly away from the cupola and at the ends remote from the cupola they have 105 portions 25 inclining downwardly. A second or guide rail is arranged above the rail 24-25. This guide rail comprises a portion 26 parallel with the portion 24 and spaced apart therefrom, and portions 27 and 28 parallel with the pawls 23 when in normal position, and with the portions 25 of the rails 24 respectively. The portions 25-28 of the rails 24-26 are arranged to return the rollers 19 and the rear end of the tilting 110 frame substantially to normal position.

The charger boxes are placed upon the tilting frame and removed therefrom in any suitable manner, but preferably by means of a suitable crane not shown, having a cable 120 29 attached to a bridle bar 30. Yokes 31 are connected with the ends of the bar, and these yokes are adapted to engage trunnions or laterally extending headed pins 32 at the opposite sides of the charger box. It will 125 be noted referring to Fig. 1, that the yokes are substantially C shaped, each including an upper arm connected to the bridle bar, and a lower arm which is normally substantially horizontal, and the lower arms have their 130

upper edges cut away as shown at 33, to receive the pins 32, which engage the yokes at the ends of the cut away portions. The arrangement is such that when the bridle bar 5 is lowered the yokes will drop below the level of the pins, as indicated in dotted lines in Fig. 1, so that they do not interfere with the forward movement of the box. When the empty box has been returned to the position of Fig. 1, lifting movement of the bridle bar will re-engage the yokes with the pins, to enable removal of the empty box.

The improved charger may be controlled by a single operative. By means of the 15 crane the operative picks up a loaded box, and delivers it to the tilting frame of the carriage pertaining to the cupola to be charged. Lowering the yokes 31, he will then operate the valve controlling the flow 20 of fluid under pressure to and from the cylinder 12, to move the piston in a direction to allow the carriage with its load to run toward the cupola under the influence of gravity.

25 The movement of the carriage may be nicely controlled, and as the carriage moves toward the stop 17, the frame 7 is gradually tilted, not sufficient however to discharge the contents of the box, all of the discharge 30 being on the outward movement of the box.

When the carriage has engaged the stops 17, the movement thereof is reversed. The rollers 19 have passed the switches 23, and as the carriage moves backward, they are diverted into the trackway between the rails 35 23—24—25 and 26—27—28. The frame is tilted further, as it moves outward and the whole of the charge in the box is distributed on top of that already delivered. Thus the 40 charge is evenly distributed throughout the cross-sectional area of the cupola stack.

When the carriage leaves the position of Fig. 1, the yokes 31 are lifted, the empty box is removed to the place of refilling, and a 45 filled box may then be delivered to the same, or another cupola. One crane and operator may serve several cupolas, as for instance three. The charge is laid onto the contents of the cupola instead of being dropped, so that the coke is not broken, there is a minimum risk of injury to the refractory lining, and the tipple and charger box are never in the cupola long enough for the heat to damage them. Since the charging opening is at 50 about the level of the top of the material in the cupola, high stack cupolas are not essential, so that the construction is more economical than with the usual process.

55 The charge fed at each operation may be as large as required, so that the device is not limited to cupolas of relatively small capacity, although it is equally well adapted for such cupolas. No part of the charging mechanism is subjected to the heat of the cupola except the charging boxes and the

tipple frame which are easily renewable. These parts however are subjected to the heat only for a minimum length of time. The principal part of the charging operation is accomplished by gravity, power being required only to return the carriage and empty box.

Once adjusted to give the best distribution of charge for various kinds of materials, the charging mechanism will automatically 75 repeat at every operation. The first cost is low, and the operating and maintenance costs are also low. The front end of the charging box bottom lays the charge instead of dumping or chuting and there is no long 80 drop to cause jar or shock. A minimum of labor is required in charging, and the device can be served by standard overhead cranes or trolleys.

While fluid pressure controlled mechanism 85 is utilized in the present instance to control the movement of the loaded carriage under gravity, it is obvious that any other suitable means might be substituted. Gravity is utilized to move the load, and power to return the empty carriage. Thus the power consumption is extremely low.

What is claimed as new is:

1. In a cupola having a charging opening, means to support and guide a charging box 95 through the opening into and out of the cupola, mechanism for tilting the box as it moves toward and from the cupola, said mechanism including means to gradually tilt the box to a position just short of discharging as it moves into the cupola, and other means to abruptly further tilt the box to discharge the contents thereof as it begins its movement of withdrawal, thereby to spread said contents in a layer from the rear to the front of the cupola.

2. In a cupola having a charging opening, means to support and guide a charging box under the influence of gravity through the opening into and out of the cupola, mechanism for tilting the box as it moves toward and from the cupola, said mechanism including means to gradually tilt the box to a position just short of discharging as it moves into the cupola, and other means to abruptly further tilt the box to discharge the contents thereof as it begins its movement of withdrawal, thereby to spread said contents in a layer from the rear to the front of the cupola.

3. In a cupola having a charging opening, means to support and guide a charging box through the opening into and out of the cupola, mechanism for tilting the box as it moves toward and from the cupola, said mechanism including means to gradually tilt the box to a position just short of discharging as it moves into the cupola, means to abruptly further tilt the box to discharge the contents thereof as it begins its movement of withdrawal, thereby to spread said

contents in a layer from the rear to the front of the cupola, and other means to return the box to its normal position as the movement of withdrawal is completed.

5. 4. In a cupola having a charging opening, a trackway to support and guide a charger box for movement through the opening into and out of the cupola, said trackway inclined to cause the box to move by gravity 10 toward the cupola, tilting mechanism for the box including means to gradually tilt the box as it moves into the cupola to an inclination just short of discharge, means to further tilt the box to discharging position as it commences its movement of withdrawal, means 15 to restore the box to normal position at the completion of the movement of withdrawal, and power operated means for moving the box away from the cupola and for controlling the movement thereof toward the cupola.

5. In a cupola having a charging opening, charging mechanism including a carriage moving by gravity toward the charging 25 opening, means to control the movement of the carriage toward the opening and to return the same, a tilting frame at the front end of the carriage for supporting a charger box, mechanism to tilt the frame as the carriage moves toward and from the cupola, said mechanism including means to gradually tilt the box to a position just short of discharge as it reaches the end of its inward movement, means to impart a sharper tilt to 30 the frame as the carriage commences its movement of withdrawal, and other means to gradually return the box to normal position at the end of the movement of withdrawal.

40. 6. In a cupola having a charging opening, charging mechanism including a carriage moving by gravity toward the charging opening, means to control the movement of the carriage toward the opening and to return the same, a tilting frame at the front end of the carriage for supporting a charger box, mechanism to tilt the frame as the carriage moves toward and from the cupola, said mechanism including means to gradually tilt the box to a position just short of discharge as it reaches the end of its inward movement, means to impart a sharper tilt to 45 the frame as the carriage commences its movement of withdrawal, and other means to gradually return the box to normal position at the end of the movement of withdrawal, and means for engagement by the carriage to positively check the movement thereof just before the charger box reaches the rear 50 wall of the cupola.

60. 7. In a cupola having a charging opening, charging mechanism including a carriage moving by gravity toward the charging opening, a tilting frame at the front end 65 of the carriage for supporting a charger

box and extending beyond the carriage to support the box with approximately half the length thereof beyond the carriage end, means to control the movement of the carriage toward the opening and to return the 70 same, and mechanism for tilting the frame as it moves toward and from the cupola, said mechanism including means to gradually tilt the frame to a position just short of discharging as it reaches the end of its inward 75 movement, means to further tilt the box to discharge the contents as the carriage commences its return movement, and other means to gradually return the frame to normal 80 untilted position as it reaches the end of its outward movement.

8. In a cupola having a charging opening, charging mechanism including a track inclining downwardly toward the opening, a carriage on the track, a tilting frame at the 85 forward end of the carriage, said tipple having means to support a charger box with the end toward the cupola open, means to control the movement of the carriage toward the cupola under the influence of gravity, and mechanism for tilting the frame as it moves toward and from the cupola, said mechanism including means to gradually tilt the frame to a position just short of discharging as it reaches the end of its inward 90 movement, means to further tilt the box to discharge the contents as the carriage commences its return movement, and other means to gradually return the frame to normal 95 untilted position as it reaches the end of its outward movement, and stops on the track to limit the movement of the carriage toward the cupola, so placed that the frame will extend into the cupola and to near the rear wall thereof when the stops are engaged 100 by the carriage.

9. In a cupola having a charging opening, charging mechanism including a track inclining downwardly toward the opening, a carriage movable on the track, a tilting frame at the forward end of the carriage for supporting a charger box and so placed with respect to the carriage that the weight of the box will normally prevent tilting of the frame, mechanism for tilting the frame 110 as the carriage moves toward and from the cupola, said mechanism including means to gradually tilt the box to a position just short of discharge as it reaches the end of its inward movement, and means to further 115 tilt the box to discharge the contents thereof as it begins its movement of withdrawal, said mechanism including rollers at the rear of the frame, trackways one above the other inclining in opposite directions to the horizontal for engagement by the rollers, and switches for deflecting the rollers from the lower to the upper trackways when the box 120 commences its return movement from the cupola.

10. In a cupola charger, a tipple, and means to place the boxes on the tipple and remove them therefrom, including yokes, each having a substantially horizontal arm 5 with recesses on the upper edge thereof, the boxes having laterally extending pins to rest in the recesses, said arms engaged and disengaged by relative vertical movement of the yokes and box.
11. In a cupola charger, a tipple, and means to place charger boxes on the tipple, and remove them therefrom, each box having at each end a pair of laterally extending pins, a bridle bar provided at each end with
- a depending yoke, each yoke including an upper arm connected with the bridle bar and a lower arm extending substantially horizontal, and recessed on its upper edge to receive the pins of the charger box, and to be engaged with and disengaged from the pins by relative vertical movement of the yokes and box.

Signed at Birmingham, in the county of Jefferson and State of Alabama, this 13th day of May A. D. 1926.
